FOREIGN PATENT DOCUMENTS

WO DM213517 12/2020

Primary Examiner — Cynthia R Underwood*(74) Attorney, Agent, or Firm* — McAndrews, Held & Malloy, Ltd.(57) **CLAIM**

The ornamental design for a trailer frame bracket, as shown and described.

DESCRIPTION

FIG. 1 is a top and front perspective view of a trailer frame bracket showing my new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom and rear perspective view thereof;

FIG. 9 is a top and front perspective view of a trailer frame bracket showing my new design according to a second embodiment;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is a bottom and rear perspective view thereof.

The dashed broken lines in the figures illustrate portions of the trailer frame bracket that form no part of the claimed design.
